UNITED STATES PATENT OFFICE.

JAMES B. HARLEY, OF FALL RIVER, MASSACHUSETTS, ASSIGNOR TO THE AMERICAN PRINTING COMPANY, OF SAME PLACE.

DESIGN FOR PRINT-CLOTH.

SPECIFICATION forming part of Design No. 17,414, dated June 28, 1887.

Application filed May 10, 1887. Serial No. 237,774. Term of patent 7 years.

To all whom it may concern:

Be it known that I, JAMES B. HARLEY, of Fall River, in the county of Bristol and State of Massachusetts, have invented and produced 5 a new and original Design for Print-Cloths, of which the following is a specification, reference being had to the accompanying photograph, forming part thereof.

In the accompanying photograph the several component parts of a hood are illustrated in plan views, and to each side of the part marked "Crown" is a representation in reduced size of a completed hood in side view.

The leading feature of my design consists in 15 the outline or pattern of the several parts of an ordinary hood or bonnet for the head.

At the top right hand of the photograph the part marked "Front" is the portion of the hood which spans the head transversely, and 20 the respective strings are shown to the left hand of the photograph, and are marked "Strings." Near the center of the illustration is shown the "Cape" of the hood, which is integral with the annexed part marked "Crown," 25 which is designed to form the back or center

portion of the completed hood, as shown in the reduced views above referred to. The front, cape, crown, and the strings of the hood are marked or outlined in broken lines.

I have shown the body of the several parts 30 of the hood as ornamented with small print figures and the ends of the strings and the borders of both the front and cape as somewhat more elaborately ornamented. However, it is to be understood that the hood or 35 bonnet design may be made in plain outline without the ornamentation I have shown, and still be within the spirit of my invention.

Having thus described my new and original design, I claim as new and desire to secure by 40 Letters Patent—

The herein shown and described print-cloth hood design, the design consisting in the outline or pattern of the several component parts of a hood or bonnet, substantially as herein set 45 forth and illustrated.

JAMES B. HARLEY.
